S. W. BIDWELL.
SASH FASTENER.

No. 37,671.

Patented Feb. 17, 1863.

Samuel W. Bidwell

UNITED STATES PATENT OFFICE.

SAMUEL W. BIDWELL, OF HARTFORD, CONNECTICUT.

IMPROVEMENT IN SASH-FASTENERS.

Specification forming part of Letters Patent No. 37,671, dated February 17, 1863.

To all whom it may concern:

Be it known that I, SAMUEL W. BIDWELL, of Hartford, in the county of Hartford and State of Connecticut, have invented certain new and useful Improvements in Window-Sash Fasteners; and I do hereby declare that the following is a full, clear, and exact description of the same, reference being had to the accompanying drawings, making a part of this specification, and to the letters of reference marked thereon, in which—

Figure 1 shows a side view of the sash lock or fastener. Fig. 2 is a front view of the same. Fig. 3 is a side view of the swinging catch-piece c. Fig. 4 is a front view of the same, and Fig. 5 illustrates a modification of my invention.

Similar letters of reference denote the same part in the several figures.

My invention relates to a lock or fastener to prevent the opening of windows from the outside, having for its object the production of an effective sash-lock, which shall be simple in its construction, which shall render the window self-locking when the sashes are closed, and which shall be capable of being so arranged that the sashes may be locked when the upper sash is lowered some distance for purposes of ventilation, as hereinafter set forth; and to this end my said invention consists in the employment, in or on the frame of the window-casing, of a perforated plate, to the back of which is hinged a double pronged swinging catch-piece, the two prongs of which, when the sashes are closed, protrude through the perforations of the plate, and lock the two sashes, substantially as hereinafter clearly described.

To enable others skilled in the arts to make and use my invention, I will proceed to a description thereof.

In the accompanying drawings, a is an oblong metallic plate, to the back of which is hinged, at b, the upper end of a swinging piece, c, the lower end of which is formed into two prongs, d and e, which project at a right angle from the body of c, and protrude through two apertures, f and g, made through the plate a. The swing-piece c, of the form shown in Fig. 1, is so shaped that the greater part of its

weight lies back of the joint b, whereby, when the plate a is perpendicular, the swing-piece c hangs in such position that its catch-prongs d and e protrude nearly their whole length through the apertures f and g.

The apparatus made as above described is shown in Figs. 6, 7 and 8, as applied to a window. Fig. 6 being an elevation, partly in section, of portions of the casing and of the upper and lower sashes, Fig. 7 a section through part of the casing, showing the upper sash, the parting strip having been removed, and Fig. 8 a vertical cross-section through both sashes, in which figures h is the pulley stile of the casing, i is part of the lower sash, k part of the upper, and l the parting-strip. The pulley-stile h is excavated sufficiently to receive the swing-piece c of the sash-lock, and to allow it to swing back so far that the points of the catch-prongs, will not protrude beyond the face of the plate a, as shown by dotted red lines in Figs. 6 and 7. The plate a, covering and hiding the aperture in the stile h, is firmly secured thereto by screws, and is so located that the catch-prongs d and e lie one on either side of the parting-strip l, and at such a height that when both the sashes are closed the inner catch-prong, d, will protrude just above the upper edge of the rail of the lower or inner sash, i, while the outer prong, e, enters a notch, m, which is made in the edge of the stile of the upper sash, k, thereby locking the two sashes so that the upper one cannot be lowered nor the lower one raised. When the swing-piece c is pushed back, as may easily be done by pressing in the prong d, the window may be opened, as both sashes are thus unlocked, but whenever the window is closed the swing-piece c will swing forward into its normal position, with the prongs d and e protruding, thus making the window self-locking when closed.

Above the notch m one or more notches, n, may be made in the edge of the upper sash, into which the prong k will enter when the upper sash is lowered some distance, by which arrangement the window may be opened a little at the top, when this is desired, and yet may be kept securely locked.

Although I prefer to make the swing-piece

c of such shape that its own weight will operate it, yet it may, in order to save weight of metal, have at its back a spring, *o*, (see Fig. 5,) to press its catch-prongs outward.

Having thus described my invention, what I claim as my invention, and desire to secure by Letters Patent, is—

The double-pronged swinging catch-piece *c*, in combination with the perforated suspen-

sion-plate *a*, the whole constructed substantially in the manner hereinbefore described, and operating to lock both sashes of a window, as set forth.

SAMUEL W. BIDWELL.
